APPARATUS FOR METAL CASTING

Percy Pritchard, Barnt Green, England

Application August 5, 1940, Serial No. 351,514
In Great Britain August 19, 1939

7 Claims.

(Cl. 22—57)

The invention relates to apparatus for the casting of metals under pressure.

An object of the invention is to bring the die, or a part to complete a die, above a container for liquid metal such as a furnace in the proper relationship for forcing the metal up into the die under fluid pressure and to remove the die or part of the die therefrom after casting and turn it over in the course of removal so that its interior is more readily accessible.

Another object is to provide an arrangement of multiple levers or arms in pivotal relation with the die or die part and with a source of power by which they may be operated to move the die or die part and turn it over in the process of moving it to or from the furnace or container for liquid metal.

Another object is to combine with such means for swinging and positioning a die, power means on which the furnace or container for liquid metal is arranged and by which tight closure against the die can be effected.

Another object is to provide power means for operating latching and stripping means for connecting the die to the furnace and separating parts of the die after the casting operation.

In one preferred construction the furnace having a pot for containing liquid metal is mounted on a vertically moving pneumatic or hydraulic cylinder. A roll over platen or frame is carried at each end thereof by two arms pivoted about different centres and operated hydraulically and/or pneumatically so that they can be swung from an approximately horizontal position in which the platen is away from the furnace to a position in which the platen is inverted and held above the furnace. The top part of the die is bolted to this platen which also carries a hydraulic cylinder for operating ejector plungers and mechanism which enter the top part of the die.

One preferred construction in accordance with the invention is illustrated in the accompanying drawings.

Figure 1 shows an elevation in part section of the apparatus with the roll over platen carrying a die part in its position remote from the furnace ready for inspection.

Figure 2 shows a similar view to Figure 1 with the roll over platen above the furnace and the furnace forced down by the ejector mechanism to separate the die parts.

Figure 3 shows a sectional view of the furnace container, die parts and part of the roll over

platens in position ready to commence the actual casting operation.

Figure 4 shows a similar view to Figure 3 with the die parts separated in the position to which they would be moved after the casting operation and just prior to the platen being swung away from the furnace.

The apparatus consists essentially of the cylinder 1 with its vertically moving ram 2 which carries a gas fired furnace 3, and of the cylinder 4 having a piston 5 which operates a pair of pivoted arms 6 when fluid pressure is supplied to the cylinder. The arms 6 are arranged one on each side of the machine keyed to the shaft 7 and carry in pivotal bearings 8 a roll over platen 9. The platen has side members 10 which are also pivoted at 13 to the free ends of a pair of arms 11 that are freely pivoted at 12 to the cylinder. The arms 6 act as drivers and the arms 11 as followers which, owing to the fact that they are pivoted about different centres from the arms 6, cause the platen 9 to roll over when the arms 6 are operated as indicated by the chain dotted lines in Figure 1. A table 14 is provided to support the platen in the open position of the dies and the platen carries a hydraulic cylinder 15 mounted on a die casing 19 by means of the three pillars 16 which casing is secured to the platen. The ram of this cylinder (see Figure 3) 20 is connected by the pillars 17 to a member 18 which slides in the die casing 19 and which is adapted to carry ejector rods 20 or other means for ejecting the casting from the die. The upper part of the die 21 is bolted to the platen through the intermediary of the die casting 19 and the lower part of the die 22 is carried by the furnace 3.

It is preferable to use an open ended pot 23 as the container for the liquid metal and to place on this a lid 24 having a nozzle or spout 25 which is enlarged at its upper end so that its cross section bears the correct relation to the adjacent cross sections of the casting to ensure efficient feeding. It is then preferable to mount the lower part of the die 22 on top of and in contact with the lid 24.

In the drawings the die is shown for making a complicated circular casting from an aluminum or other light metal alloy.

50 A sand core 28 on a metal carrier 35 is also placed in position on the pillar part 36 of the die and secured by a locking pin 31. The open metal container 23 is filled with liquid metal and lowered into the furnace or if already in the furnace is filled with liquid metal from a ladle. The lid

24 and feeding nozzle 25 and the lower part 22 of the die are then placed on the container or pot with the interposition of suitable asbestos jointing washers 38. The fluid-pressure means 4, 5 are now operated to swing the arms 6 carrying the platen 9 so that the platen is turned over to bring the die on its underside and into a position accurately located above the furnace as shown in Figure 2. The furnace is raised by means of its fluid pressure cylinder to bring the two parts 21 and 22 of the die into contact and clamp them together, while suitable hydraulic or pneumatic locking bolts 39 are shot to hold the two die parts together and to secure the lower part 22 of the die to the furnace 3, as shown in Figure 3. Dowels 40 or other suitable guiding means may be provided to ensure the accurate relative location of the die parts.

The casting is now made preferably by means of compressed air forced into the metal container through the inlet 42, which forces the metal up the nozzle into the die. As soon as the casting has set the pin 37 which holds the core is released and the ejector cylinder 15 is energised to project a number of plungers 20 which bear on the casting and also on the lower part of the die, and so separate the two die parts 21 and 22 and eject the casting from the upper part of the die 21 as shown in Figure 2. This movement is possible due to the fact that the pressure exerted by the ejector cylinder 15 is greater than that exerted by the cylinder 1 supporting the furnace 3 so that the ejector cylinder is able to force the casting in the lower part of the die and the furnace downwards.

In certain cases, as for instance, when the upper part of the casting contains a number of parts such as fins of small cross sectional area, and the lower part is of large cross sectional area, the upper part may require to be ejected from the die after a comparatively short time in order to avoid setting up contraction stresses between itself and the die, whereas the lower part of the casting may require a much longer period to enable the mould to be fed slowly. With the previously known apparatus the casting would have to be made and ejected in a time which is only a compromise between these two requirements. With the present apparatus it is possible to eject the upper part of the casting from the upper part of the die before the lower part of the casting has been finished, since the lower part of the die is still firmly pressed into contact with the furnace the metal can continue to be fed under pressure from the furnace into this lower part of the die, provided a sufficient mass of metal has already set in its upper part to form a seal.

After the casting has been finished and ejected from the upper part of the die the furnace is lowered to the position shown in Figure 4, the platen with this upper part of the die may then be swung back to the position shown in Figure 1 leaving the casting with its sand core in the lower part of the die on top of the furnace from which it is subsequently removed.

Since all these operations apart from cleaning or assembling the die, attaching the core and refilling or replacing the container are done by 70 hydraulic or pneumatic means, the apparatus can be conveniently controlled from a remote control cabin, not shown, or other place shielded from the casting apparatus and the process merely consists of operating a series of valves in the 75

right sequence at the right speed and for the right duration.

This is illustrated diagrammatically in Figure 2 which shows the grouped control valves and the various leads from these valves to the apparatus. Oil under pressure is supplied by the pipe 58 and is led via the control valve 51 and the lead 52 to the cylinder 4 operating the throw over arms, on release the oil from the lead 52 is returned to the sump via the lead 53. The raising or lowering of the furnace is done hydraulically, being controlled by the valve 54 and supplied via the lead 55, the release to the sump being via lead 56. The hydraulic power is also used to operate the ejector 15. It is controlled by valve 57, the lead 58 causing a downward or ejecting movement of the ram and the lead 59 the return or upward movement; while the lead 60 is the release to the sump. Compressed air from the main 61 can be admitted by the valve 62 to the lead 63 to shoot the locking bolts and secure the two halves of the mould and is admitted to the lead 64 to withdraw the bolts in each case the exhaust is to atmosphere via the lead 65. In a similar way valve 66 controls the bolts to secure the lower half of the mould to the furnace. The lead 67 is for shooting the bolts, the lead 68 for withdrawing them and the lead 69 for exhausting to atmosphere. Compressed air from mains, a receiver or other device is admitted by the valve 70 to the lead 42 which takes it to the container 23 to force the metal into the mould the pressure being read on the manometer 71. The valve 72 is for exhausting the lead 42 to atmosphere. The operation can be facilitated either by combining or interlocking the controls of these valves or by providing an indicator device which is worked in conjunction with the valves and which shows by means of pilot lights which valve is to be operated next. This simplification of the operation of the apparatus enables it to be operated rapidly and easily even by comparatively unskilled workmen, thus effecting a very considerable economy, both in time and wages.

I claim:

1. Apparatus for casting metals by fluid pressure comprising a container in which metal can be maintained liquid, means adapted to carry a die or part of a die, said means being movable from a position in which the die is remote from the container and in inverted position to a position in which the die is above the container, said means being operable to turn the die to upright position during such movement, and means for bringing the die and container together and holding them tightly in contact during the casting process.

2. Apparatus for casting metals by fluid pressure, comprising a heating furnace adapted to receive a pot of metal, means for moving the furnace upwardly and downwardly, means supporting a die, said means being movable from a position in which the die is remote from the furnace and inverted to a position in which the die is above the furnace, said means being operable to turn the die upright during such movement.

3. Casting apparatus comprising a heating furnace in which a pot containing liquid metal can be placed, a die part, means supporting the die part and operable to move it into a position above the furnace, means for moving the die and furnace toward each other, means for holding said die parts together, pressure means for forcing

metal from the pot into the die, and means for ejecting the finished casting from the die part, said means for ejecting the casting having sufficient force to overcome the means which hold together the two die parts.

4. Apparatus for casting metals by fluid pressure comprising a heating furnace, means for raising and lowering the furnace, pivoted arms supporting a member to which a die part can be attached, means for moving the pivoted arms from a substantially horizontal position in which the member supported thereby is removed from the furnace to a substantially vertical position in which said member is positioned vertically above the furnace, said arms being so connected to the member that the member is turned over as the arms are moved from their horizontal to their vertical position.

5. Apparatus for casting metals by fluid pressure comprising a heating furnace, a vertically arranged pneumatic or hydraulic cylinder having a piston connected to the furnace by which the furnace can be raised or lowered, a platen supporting a die part and carried at the ends of two arms which are pivotally supported adjacent the furnace at their other ends, pneumatic or hydraulic means for swinging the arms from an approximately horizontal position in which the platen is removed from the furnace to a position in which the platen is above the furnace in a position adjacent a second die part, a third arm connected at its one end to the platen and pivoted at its other end adjacent the furnace at a point spaced from the pivotal supports of the two first-mentioned arms, said third arm being operable to invert the platen during said movement of the platen, and a hydraulic cylinder carried by the platen and having power operated means to which ejector rods are attached, said ejector rods being operable by the cylinder to separate the die parts for the removal of the casting therefrom.

6. Apparatus for casting metals by fluid pressure comprising in combination a heating furnace, a pot therein for containing liquid metal, a

- vertically arranged power cylinder beneath the furnace having a piston by which the furnace can be raised or lowered, a die-supporting member carried at the ends of two arms which are pivotally supported adjacent the furnace at their other ends, power means for swinging the arms from an approximately horizontal position in which the die-supporting member is removed from the furnace and is inverted to a position in which said member is positioned above the furnace adjacent a second die part, means for turning said member to upright position during such movement, means for supplying fluid under pressure to said pot to cause liquid metal therein to be forced into the die, power operated means carried by the die-supporting member, and ejector rods attached to said power operated means and being adapted to separate the die parts for the removal of the casting.
- 20 7. Apparatus for casting metals by fluid pressure comprising in combination a heating furnace, a removable pot in said furnace adapted to contain liquid metal, a vertically arranged power cylinder having a piston connected to the furnace whereby the furnace may be raised or lowered, a die-supporting platen, two arms having their one ends pivotally connected to the platen and their other ends pivotally supported adjacent the furnace, power means for swinging the arms from an approximately horizontal position in which the platen is removed from the furnace to a position in which the platen is above the furnace and adjacent a second die part, means for inverting the platen during such movement, power operated means carried by the platen to which ejector rods are attached and which are operable to separate the die parts for removing the casting therefrom, means for supplying fluid under pressure to said pot to force liquid metal therefrom to the die, and a cover for said pot which carries a delivery nozzle depending into the pot, said cover supporting said second die part.

PERCY PRITCHARD.
